BAFFLE FOR WATERTUBE BOILERS

George P. Reintjes, Kansas City, Mo.

Application November 16, 1944, Serial No. 563,709

3 Claims. (Cl. 110—98)

1

This invention relates to improvements in the efficiency of water tube boilers by a system of baffles whereby it is possible to transfer more heat into the tubes than with other baffle systems with which I am familiar.

In a straight tube boiler, one or more steam and water drums usually overly and parallel the tubes, the end of said tubes being ordinarily connected to headers, which, in turn, are connected to the steam drums. It has been found that those tubes directly underlying the steam drum are most efficient in the production of steam since they are straighter and offer less resistance to flow; consequently to improve boiler heating capacity, it will be evident that these tubes should be exposed to as much radiant heat as possible and that they should also be heated to the greatest extent possible by convection.

An object of the invention, therefore, is to provide a combination of horizontal and vertical baffles of such nature that the center tubes, that is, the tubes lying between vertical planes coinciding with the diameter of the boiler drum, shall be exposed to cross flow of the combustion gases, said cross flow having been found to be more efficient in transferring heat than flow paralleling the tubes.

A further object of the invention is to increase the overall efficiency by proportioning the passes to the volume of gases, decreasing the area of the passes as the gases cool so as to maintain a constant or greater velocity, and effecting turning or deflection of the gases to as great extent as possible, in an unrestricted open chamber above the tube bank and in front of the curtain wall, which materially lessens frictional resistance and accommodates more gases or the same volume of gases with less stack height.

With the general objects named in view, and others as will hereinafter appear, the invention consists in certain novel and useful features of construction and combination of parts as herein-after described and claimed; and in order that it may be fully understood, reference is to be had to the accompanying drawings, in which:

Figure 1 is a central vertical section taken through a water tube boiler of standard design, equipped with the baffles of the invention.

Figure 2 is a section on the line II—II of Figure 1.

Figure 3 is a section on the line III—III of Figure 1.

Figure 4 is a section on the line IV—IV of Figure 1.

2

Figure 5 is a section on the line V—V of Figure 1.

Figure 6 is a cross section through a slightly modified form of baffle construction in which the vertical baffles forming the main or cross-flow pass are arranged in Venturi tube fashion.

Figure 7 is a cross section through the same general type of furnace having a steam superheater above the tube bank.

10 Figure 8 illustrates a wider combustion chamber in which there are two or more main or cross-flow passes.

Figure 9 is a perspective view of the furnace with the boiler tubes and walls largely broken away to more clearly disclose the baffles.

In the said drawings, where like reference characters identify corresponding parts in all of the figures, 1 is the steam drum of any conventional boiler, said drum being connected to front 20 and rear headers 2 and 3, which are interconnected by boiler tube bank 3a, the boiler as a whole being supported on any suitable setting 4 and providing a furnace combustion chamber 5. The furnace is constructed with a curtain wall 6 25 separating the gas and turn chamber 7 from the stack or outlet end of the furnace 8, and a horizontal baffle extending from the lower edge of the cross baffle to the back wall of the outlet chamber and from side wall to side wall of said 30 chamber to close direct communication between the outlet chamber and the fire box.

In the present embodiment of the invention, a horizontal lower baffle 9 is arranged above the second row of boiler tubes, said baffle extending 35 from the rear to the front end of the furnace. This horizontal baffle 9 is cut-away, preferably equal distance from the center line of the furnace from a point vertically below the curtain wall 6 to the front end of the furnace, to provide a main cross-flow pass 10 for the combustion gases leading entirely through the bank of tubes to the turn chamber 7 above the same and below the boiler drum. The gases are preferably confined 40 to the central portion of the tube bank by a pair of upwardly extending baffles 11, running longitudinally of the furnace shown in the present embodiment as being inclined toward each other, their lower ends being in juxtaposition with the 45 inner edges of the cut-away portion of the horizontal baffle 9.

The gases are prevented from flowing into the rear section of the bank of tubes by means of a vertical cross baffle 12 extending from baffle to baffle 11. This construction prevents by-passing 50

of the flame and combustion gases to the rear or stack end of the furnace.

In order to force the gases rearwardly in counterflow relation and to maintain as great a wiping action on the tubes as is possible, a pair of upper horizontal baffles 13 extend from the opposite ends of the longitudinal baffles 11 to the side walls of the furnace. Thus, the baffles 13 in conjunction with the lower baffles 9, the side walls of the furnace and the longitudinally extending baffles 11, produce a pair of counterflow passes 14 leading into the economizer or rear section of the tube bank back of the curtain wall 6 and baffle 12.

In the construction shown in Figure 6, vertical baffles 15 are arranged in Venturi-tube fashion and the boiler drum 16 is protected against direct impingement of the combustion gases by means of a dividing baffle 17. In this construction, the horizontal baffles 13 provide a soot trap or space 18 by omission of a portion of the boiler tubes. The construction shown in Figure 7 is similar to that of Figure 6, but illustrates one method of accommodating a steam super-heater 19, the combustion gases being forced through the center part of the same by a pair of vertically extending walls 20 super-imposed on the upper ends of the vertical main cross-pass baffles 21.

It will be apparent that various modifications may be employed when the baffle system is used in wide furnaces. For example, in Figure 8 a construction is shown in which a pair of main cross-flow passes 22 and 23 communicate with one common longitudinal flow pass 24.

From the above description and drawings, it will be apparent that I have produced a construction embodying all of the features set forth as desirable, and while I have illustrated and described the preferred construction, it is to be understood that I reserve the right to all changes within the spirit and scope of the appended claims.

I claim:

1. The combination in a water tube boiler having front and rear headers connected by a bank of water tubes in vertically and horizontally spaced rows, a roof spaced above said tubes, a fire box below the tubes, a bridge wall dividing the space above the tubes into a gas turn chamber and a gas outlet chamber, and side and end walls enclosing the tube bank and fire box, an outlet connection for the gas outlet chamber, of a plurality of spaced longitudinal baffles extending longitudinally of and upwardly through the tube bank from a point below the bridge wall to one end wall of the furnace, a cross baffle extending upwardly through the tube bank from a point below the bridge wall to the lower edge of the bridge wall to close communication between the space between adjacent longitudinal baffles and the outlet chamber, horizontal baffles extending from the side walls of the furnace to the lower edges of adjacent longitudinal baffles to confine upward gas flow to the space between said longitudinal baffles, and a horizontal baffle extending from the lower edge of the cross baffle to the back wall of the outlet chamber and from side wall to side wall of said chamber to close direct communication between the outlet chamber and the fire box.

2. The combination in a water tube boiler having front and rear headers connected by a bank

of water tubes in vertically and horizontally spaced rows, a roof spaced above said tubes, a fire box below the tubes, a bridge wall dividing the space above the tubes into a gas turn chamber and a gas outlet chamber, side and end walls enclosing the tube bank, fire box and outlet chambers, and an outlet connection for the gas outlet chamber, of a pair of spaced longitudinal baffles extending longitudinally of and upwardly through the tube bank from a point below the bridge wall to one end wall of the furnace, a cross baffle extending upwardly through the tube bank from a point below the bridge wall to the lower edge of the bridge wall to close communication between the space between said pair of longitudinal baffles and with the outlet chamber, horizontal baffles extending from the side walls of the furnace to the lower edges of the longitudinal baffles to confine upward gas flow to the space between said longitudinal baffles, and a horizontal baffle extending from the lower edge of the cross baffle to the back wall of the outlet chamber and from side wall to side wall of said chamber to close direct communication between the outlet chamber and the fire box.

3. The combination in a water tube boiler having front and rear headers connected by a bank of water tubes in vertically and horizontally spaced rows, a roof spaced above said tubes, a fire box below the tubes, a bridge wall dividing the space above the tubes into a gas turn chamber and a gas outlet chamber, side and end walls enclosing the tube bank, fire box and outlet chamber, and an outlet connection for the gas outlet chamber, of a pair of spaced longitudinal baffles extending longitudinally of and upwardly through the tube bank from a point below the bridge wall to one end wall of the furnace, a cross baffle extending upwardly through the tube bank from a point below the bridge wall to the lower edge of the bridge wall to close communication between the space between said pair of longitudinal baffles and the outlet chamber, horizontal baffles extending from the side walls of the furnace to the lower edges of the longitudinal baffles to confine upward gas flow to the area between the first-named baffles, a horizontal baffle extending from the lower edge of the cross baffle to the back wall of the outlet chamber and from side wall to side wall of said chamber to close direct communication between the outlet chamber and the fire box and horizontal upper baffles extending from the upper ends of the longitudinal baffles to the side walls of the furnace from the bridge wall to a point short of the front wall of the furnace.

GEORGE P. REINTJES.
